Primary Examiner — Robert M Spear*Assistant Examiner* — Ryan Harvey(74) *Attorney, Agent, or Firm* — Price Heneveld LLP(57) **CLAIM**

We claim the ornamental design for an electric scooter frame, as shown and described.

DESCRIPTION

FIG. 1 is a front perspective view of the electric scooter frame showing the design.

FIG. 2 is a rear perspective view of the electric scooter frame showing the design.

FIG. 3 is a front elevational view of the electric scooter frame showing the design.

FIG. 4 is a rear elevational view of the electric scooter frame showing the design.

FIG. 5 is a left side elevational view of the electric scooter frame showing the design.

FIG. 6 is a right side elevational view of the electric scooter frame showing the design.

FIG. 7 is a top plan view of the electric scooter frame showing the design; and,

FIG. 8 is a bottom plan view of the electric scooter frame showing the design.

Portions of the electric scooter frame shown in broken lines form no part of the claimed design.
